United States Patent Office

Des. 181,507

Patented Nov. 19, 1957

181,507

FOOD DISINTEGRATOR BASE

Henry J. Talge and John E. Snell, Kansas City, Mo., assignors to John C. Hockery, Kansas City, Mo., as trustee

Application April 4, 1955, Serial No. 35,358

Term of patent 14 years

(Cl. D89—1)

Fig. 1.

Fig. 2.

Fig. 3.

Fig. 1 is a side elevational view of a food disintegrator base embodying our new design;

Fig. 2 is a front elevational view of the same; and

Fig. 3 is a plan view of same taken along the line 3—3 of Fig. 2 in the direction of the arrows.

The essential features of our design reside in the parts shown in solid lines, the parts shown in broken lines being only for purposes of illustration.

We claim:

The ornamental design for a food disintegrator base, as shown and described.
